(57) **CLAIM**

The ornamental design for a charging station, as shown and described.

DESCRIPTION

The file of this patent contains drawings executed in color. Copies of this patent with color drawings will be provided by the Office upon request and payment of the necessary fee. FIG. 1 is a front perspective view of the charging station showing our new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines illustrate structure or features that form no part of the claimed design.
